(57) CLAIM

The ornamental design for a light, as shown and described.

DESCRIPTION

FIG. 1 is a top perspective view of a first embodiment of a light illustrating our new design in a pendant light.

FIG. 2 is a bottom perspective view of the first embodiment.

FIG. 3 is a top view of the first embodiment.

FIG. 4 is a bottom view of the first embodiment.

FIG. 5 is a front view of the first embodiment.

FIG. 6 is a rear view of the first embodiment.

FIG. 7 is a right-side view of the first embodiment.

FIG. 8 is a left-side view of the first embodiment.

FIG. 9 is a top perspective view of a second embodiment of a light illustrating our new design in another pendant light.

FIG. 10 is a bottom perspective view of the second embodiment.

FIG. 11 is a top perspective view of a third embodiment of a light illustrating our new design in yet another pendant light.

FIG. 12 is a bottom perspective view of the third embodiment.

FIG. 13 is a top perspective view of a fourth embodiment of a light illustrating our new design in a sconce light; and, FIG. 14 is a bottom perspective view of the fourth embodiment.

The portions of the light shown in broken lines form no part of the claimed design.
